UNITED STATES PATENT OFFICE.

LOUIS L. LEADBETTER, OF HUNTINGTON PARK, CALIFORNIA.

APPARATUS FOR THE MANUFACTURE OF OILED PAPER.

Application filed January 9, 1925. Serial No. 1,447.

This invention has to do with apparatus for the manufacture of oiled paper. My present invention has particular reference to the manufacture of oiled paper, that is, a paper containing or carrying oil. Oiled paper, such as I herein refer to, is used in various industries, for example, it is being extensively used in the fruit industry for wrapping fruit. The nature of the oil employed in the paper and the oil content of the paper, varies, of course, with the uses for which it is intended and with varying conditions. In the case of paper for wrapping fruit it is desirable that the oil content be high, for instance, from ten to thirty-five per cent of oil. Further, it is desirable that the oil be impregnated in the paper so that it is carried in or throughout the body of the paper and is not simply a film or layer on the outside of the paper. In attempting to oil paper, the methods employed for waxing paper have been tried, using oil instead of wax. These methods have been more or less unsuccessful, one reason being that waxing processes are intended to put a film or layer of wax on a sheet of paper and therefore do not operate to effectively impregnate the paper even though oil is used in place of wax. Further, it has been found impossible with these methods to obtain a paper with a very high oil content.

A primary object of this invention has been to provide apparatus for successfully and practically oiling paper.

A further object of this invention has been to provide apparatus whereby a paper can be oiled so that it obtains a high percentage of oil.

The various objects and features of the invention will be best and more fully understood from the following detailed description of a typical form and carrying out of the invention throughout which description reference is had to the accompanying drawings, in which—

Fig. 1 is a side elevation of a portion of the apparatus employed in the manufacture of paper, being a view showing the calendar and a portion of the drier, and showing a portion of the apparatus provided by the present invention in operating position with relation to the drier and calendar.

Fig. 2 is a transverse sectional view of the apparatus shown in Fig. 1, being a view showing the general arrangement and rela-

tionship of the various parts provided by the present invention and

Fig. 3 is a view taken as indicated by line 3—3 on Fig. 2.

In accordance with the method carried out by this apparatus the paper may be formed and handled in the apparatus usually employed in the manufacture of paper. In accordance with the invention the paper is run through the usual drying rolls and while it is still hot or warm and before it has been hardened or compressed by the action of calendar rolls or other apparatus, the oil is applied to it. By applying the oil to the paper as it comes off of the drying rolls, the oil spreads in the paper or is taken up by the paper, the cellular formation of the paper being expanded and open so that it readily receives the oil.

The paper with the oil applied to it is passed to or through the usual calendar. The action of the rolls of the calendar is to further spread the oil throughout the paper and to squeeze or compress the paper in the presence of the oil or while the oil is in and on it, causing the oil to be carried in or throughout the finished paper and not merely on the surfaces of the paper. In practice a body of oil accumulates at the calendar rolls which receive the paper from the drier which body of oil materially spreads across the paper at the rolls so that the paper enters the calendar rolls in the presence of a body or bath of oil. Upon being calendered the desired amount or in the desired manner the paper is rolled and allowed to stand in the roll until it has cooled. The paper is warm as it passes from the calendar into the roll, so that allows the oil to stand several hours, say from six to twelve hours, allows the oil to become thoroughly and evenly distributed throughout the entire roll. I have found from actual operation that I can by this method manufacture a paper containing as high as thirty-five per cent oil and roll the paper without danger of sticking.

The apparatus provided by this invention for carrying out the method which I have just set forth comprises, generally, and in a simple form, an oiling unit or device 10 comprising a roller 11 and an oil carrying trough 12, drive means 13 for the oiling device, a control 14 for the drive means, means 15 for supplying oil to the oiling device, and means 16 for maintaining the oiling device at the proper temperature.

The oiling device, in accordance with the present invention is located ahead of the calendar 18, it being preferred to locate it between the calendar 18 and the drier 19 so that it applies the oil to the paper after it has passed out of the drier and before it has entered the calendar. The oiling device 10 comprises a roller 11 sufficiently long to extend completely across the sheet of paper being oiled. The roller is arranged parallel with the calendar rolls and is located with reference to the calendar rolls, which are to receive the paper, so that the paper must pass over it. The trough 12 is an open trough arranged in connection with the roller 11 to carry a body of oil so that the roller runs or dips into it. In the construction shown in the drawings the roller 11 and trough 12 are formed as a unit, the roller 20 being carried by the bearings provided at the ends of the trough. This unit is detachably mounted on a suitable part, for instance, the frame 19^a of the calendar so that it can be removed when not required for use. 25 In practice the unit is secured to the frame 19 of the calendar by bolts 20 and the frame of the calendar is provided at various points with holes 21 to receive the bolts 20 so that the unit can be adjusted to various heights 30 on the frame 19.

In accordance with my invention the oil O carried in the trough 12 is carried to the paper by the rotation of the roller 11 and a quantity of oil applied to the paper is regulated or varied by varying the speed of rotation of the roll 11. The drier and calendar operate to feed the paper across the roll 11 at a constant speed, so therefore variation in the speed of rotation of the roller 11 will 40 vary the amount of oil wiped from the roller by the paper passing over the roller. The drive 13 provided for the roller 11 is therefore a variable speed drive. In the particular arrangement shown in the drawings the drive is from a suitable engine or source of power (not shown) through a belt 25 running over a pulley 26. Pulley 26 is mounted on a shaft 27 carrying a conical pulley 28. 45 A second conical pulley 29 is mounted on a counter shaft 30 and a belt 31 connects the pulleys 28 and 29. The conical pulleys are, of course, oppositely arranged so that variation in the position of the belt 31 varies the speed ratio obtained between the shaft 27 and counter shaft 30. The counter shaft 30 is connected with the shaft 32 of the roller 11 by a suitable drive, for instance, a chain drive 33. In practice, when the desired speed for the roller 11 cannot be had through 50 the conical pulleys the sprockets of the chain drive 33 may be varied or changed.

The control means 14 for the drive 13 may comprise an idler pulley 40 for controlling the belt 25. I have shown the idler pulley carried on a pivoted arm 41 and a line

42 connected with the arm 41 and arranged over suitable pulleys 43 so that the arm can be operated from a handle 44 located at a suitable part of the apparatus. By operating or pulling upon the handle 44 the arm 41 is lifted so that tension is taken off the belt 25 allowing the belt to slip on the pulley 26. The line 42 and pulleys 43 are preferably arranged so that the handle 44 is at a convenient point near the oiling device so that an operator can conveniently throw the oiling device out of operation when located at or near it. Further, a suitable part 50 may be provided to hold the handle 44 in actuated position and thereby hold the idler pulley 40 released. Means provided for supplying the trough 12 with oil may comprise a suitable pump 51 arranged to receive oil from one or more barrels or tanks 52, a fluid connection 53 between the pump and trough for carrying the pumped fluid from the pump to the trough. The desired level of oil may be maintained in the trough by providing the trough with an overflow pipe 55 which may discharge into the tanks 52. Suitable control valves 56 may be provided in the connection 57 between the tanks 52 and pump 51 and suitable control valves 57^a may be provided in the pipe 55 so that the oil may be used from one or more of the tanks as desired and when a tank is emptied it may be removed and a full one replaced without stopping operation of the apparatus. It will be apparent how these operations can be carried out by suitable manipulation of the valves 56 and 57^a and by suitably connecting and releasing the tanks and the connections 55 and 57. The pump 51 may be driven from any suitable source of power for instance, from the counter shaft 30 by a belt 60.

The means 16 for maintaining the oiling device at the proper temperature may comprise steam connections with the roll and a steam pipe 62 arranged in the trough 12 to be supplied with steam from a suitable steam pipe 63. The steam after passing through the steam pipe 62 in the trough 12 may discharge through an exhaust pipe 65. Steam may be admitted into one end of the hollow roll shaft 32 from a steam pipe 63^a so that it passes into the roll. The steam may discharge from the other end of the shaft through a pipe 65^a. The desired temperature may be maintained by 115 suitable regulation of a control valve 66 and control valve 66^a provided for that purpose in the steam lines 63 and 63^a, respectively.

From the foregoing description it is believed that the operation of the invention will be fully understood. The oiling device 10 is mounted on the frame of the calendar at the desired height so that the paper P coming from the drier will pass over the 120 125 130

roller 10 before reaching the calendar. The roller is set in operation by releasing the idler pulley 40 so that the drive belt 25 is tightened on the pulley 26. The drive 13 is set to operate the roller at the desired speed and the valve 66 is regulated to maintain the oiling device at the desired temperature. With the device thus operating the paper P passing from the drier to the 10 calendar has applied to it a certain quantity of oil which oil is immediately taken up by the paper, because of the paper being warm and the cells of fibers being expanded and in condition to readily receive 15 the oil. The oil laden paper passes from the roller 11 to the calendar rolls where the oil is further distributed throughout the paper and where the paper is compressed and hardened or finished. From the calendar 20 the paper is taken while still warm and passed onto a roll 100 in which it is allowed to stand while it cools. It usually takes several hours for the roll to cool during which time the oil becomes completely and 25 uniformly distributed in or throughout the paper. It is desirable during operation to occasionally obtain a sample of unoiled paper in order to determine the oil content of the paper being produced. A sample of 30 unoiled paper may be had by operating the control 14 to stop operation of the oiling device long enough for a sample of paper to pass through the apparatus without picking up oil. By testing this unoiled sample 35 and a sample of the oiled paper taken immediately before or after it, it is possible to determine exactly what quantity of oil is being applied to the paper.

Having described only a typical preferred 40 form of my invention I do not wish to limit myself to the specific details hereinabove set forth, but wish to reserve to myself any changes or variations that may appear to those skilled in the art or fall within the 45 scope of the following claims.

Having described my invention, I claim:

1. In paper making machinery a roll to be arranged ahead of the calendar, means for supplying oil to the surface of the roll including an oil carrying trough at the roll, 50 means for heating the oil carried in the trough, and means for driving the roll at a predetermined speed.
2. In paper making machinery, a roll to be arranged ahead of the calendar, means 55 for heating the roll, means for supplying oil to the surface of the roll, and means for driving the roll at a predetermined speed.
3. In paper making machinery, a roll to be arranged ahead of the calendar, means 60 for supplying oil to the surface of the roll including an oil carrying trough at the roll, means for maintaining a constant level of oil in the trough, and means for driving the roll at a predetermined speed. 65
4. In paper making machinery, a roll to be arranged ahead of the calendar, means for supplying oil to the surface of the roll, and a releasable drive for the roll.
5. In paper making machinery, a trough 70 to be detachably mounted on the frame of a calendar, means for maintaining a constant level of oil in the trough, a roll arranged to run in contact with the oil, means for heating the oil and the roll, and a re- 75 leasable variable speed drive for the roll.
6. In paper making machinery, a roll to be arranged ahead of the calendar, means for supplying oil to the surface of the roll including an oil carrying trough at the roll, 80 means for maintaining a constant level of oil in the trough including an oil reservoir, an overflow from the trough to the reservoir, and means for pumping oil from the reservoir to the trough, and means for driv- 85 ing the roll at a predetermined speed.

In witness that I claim the foregoing I have hereto subscribed my name this 12 day of December, 1924.

LOUIS L. LEADBETTER.
